SLICING MACHINE

William J. Campbell, Indianapolis, Ind., assignor
to American Slicing Machine Company, Chi-
cago, Ill., a corporation of New York

Application January 15, 1934, Serial No. 706,713

5 Claims. (Cl. 146—102)

My invention relates to an improvement in slicing machines and has for one purpose the provision of improved supporting and guiding means for the gauge plate of a slicing machine. Other objects will appear from time to time in the course of the specification and claims.

I illustrate my invention more or less diagrammatically in the accompanying drawings, wherein—

- 10 Figure 1 is a front elevation;
Figure 2 is an end elevation;
Figure 3 is a plan view with parts broken away;
Figure 4 is a section on the line 4—4 of Figure 15 3, with the parts in a different position; and
Figure 5 is a section on the line 5—5 of Figure 3.

Like parts are indicated by like symbols throughout the specification and drawings.

- 20 Referring to the drawings A indicates any suitable base which may include, for example, the horizontal channel member generally indicated as A¹ in Figure 4. Mounted upon the base is a rotary knife B provided with a knife shaft B¹ rotatably mounted on any suitable bearing within the sleeve portion B². B³ is a driving pulley about which may pass a driving belt B⁴ to any suitable pulley not herein shown but associated with the motor B⁵ which is also mounted on the 25 base A.

- 30 The forward face of the knife is substantially masked as by a guard plate C. It is offset as at C¹, C² to permit it to penetrate the hollow of the knife B. It will be understood that the axis of 35 the knife is inclined slightly from perpendicularity to the face of the guard plate C.

- 40 Mounted for reciprocation across the face and past the cutting edge of the knife is a carriage structure generally indicated as D which is mounted, for example, on tracks D¹ and is provided with a work receiving trough D² and a pusher plate D³ mounted on any suitable guide D⁴ for movement toward and away from the cutting plane.

- 45 E is any suitable slice receiving member or tray which is mounted to the rear of the cutting plane, and is provided with a forward flange E¹ which may be at or near the cutting plane of the knife.

- 50 G generally indicates the gauge plate which is in general parallelism with the plane of the guard plate C. The gauge plate, as shown, is a simple flat plate which may be of metal and which has an arcuate edge G¹ conforming generally to the cutting arc of the knife. G² indi-

cates generally a supporting member having an upward extension or flange G³ to which the lower edge of the gauge plate G is secured as by the screws G⁴. It will be noted that the lower edge of the gauge plate extends downwardly as at G⁵ somewhat below the lower face of the flange G³, this face lying in a generally horizontal plane. G⁶ indicates a vertical face of the member G² which is generally parallel with the outer face of the flange E¹ of the slice receiver E. It will 10 be observed that when the gauge plate is in its forward position, as shown for example in Figure 2, the lower edge G⁵ of the gauge plate G lies in the plane of the flange E¹ and closely approaches the upper edge of that flange. When 15 the parts are in a different position with the gauge plate withdrawn from the cutting plane, the member or flange G³ substantially overhangs the flange E¹ but may be spaced somewhat away from it as the overhang of the edge 20 G⁵ prevents the penetration of the material into the space between the opposed faces of E¹ and G⁶. The member G² is secured as by the screws G⁷ to a sliding member G⁸ which may, if desired, be a casting. It includes the two bosses G⁹ and G¹⁰ 25 and an additional or associated boss G¹¹ adjacent or forming part of the boss G⁹. The bosses G⁹ and G¹⁰ are provided with cylindrical apertures whereby they are slidably mounted on the pins G¹², G¹⁴. As will be clear from Figure 1, 30 there is a fairly tight fit between the boss G⁹ and the pin G¹². On the contrary, the boss G¹⁰ has an aperture of somewhat greater diameter than the diameter of the pin G¹⁴. The purpose of this is to render the alignment of the parts easy 35 in assembling the machine and to prevent binding. The pins G¹² and G¹⁴ are mounted or fixed in any suitable manner upon the frame A being secured, for example, in relation to the channel member A¹. These pins may, for example, be 40 secured by transverse securing pins G¹⁵ in bosses G¹⁶, shown, for example, in Figure 3. The outer ends of the pins may be held, for example, by terminal brackets G²⁰ and G²¹ associated with the base. In order to prevent rattling and to 45 provide a take-up means, I illustrate an adjustable screw G¹⁷ in association with the boss or sleeve G¹⁰, as is shown, for example, in Figures 2 and 5. It will be noted that the pins G¹², G¹⁴ are slightly inclined in such variation that as the 50 gauge plate structure is moved rearwardly from the cutting plane, it is also moved slightly laterally away from the cutting edge of the knife. It will be noted that the supporting engagement between the gauge plate structure and the pins G¹², 55

G^{14} is positioned forwardly of the cutting plane at a point where it is readily accessible for adjustment or lubrication.

In order to impart movement to the gauge plate structure upon the pins G^{12} , G^{14} I illustrate an actuating lever generally indicated as H . The details of the lever do not of themselves form part of the present invention but I provide an exterior metal handle H^1 which may be pivoted 10 in relation to the lever as at H^2 . The lever as a whole is pivoted as at H^3 . Integral with the lever H is a supplemental lever H^4 to which is pivoted, as at H^5 , the link H^6 which, in turn, is pivoted, as at H^7 , to the actuating pin or rod H^8 . 15 H^9 is a yielding or coil spring take-up member to prevent lost motion, wear and rattling. The frame member A^1 is cut away, as at H^{10} , to permit the ready penetration of the pin or rod H^8 , there being no bearing engagement between the 20 two. The rod H^8 is secured in the boss G^{11} as by any suitable pin or screw H^{11} .

It will be realized that whereas I have described and shown a practical and operative device, nevertheless many changes might be made in the 25 size, shape, number and disposition of parts without departing from the spirit of my invention. I therefore wish my description and drawings to be taken as in a broad sense illustrative and diagrammatic rather than as limiting me to my 30 specific showing.

The use and operation of my invention are as follows:

I provide an improved supporting and actuating means for the gauge plate of a rotary knife 35 slicing machine. The function of the gauge plate is to gauge the thickness of the slices by limiting the distance the work can be thrust along the receiving trough D^2 . In operation, the user sets the gauge plate G at its desired gauging position 40 and then moves the work up against it. He then moves the carriage D across the face of the gauge plate and against the cutting edge of the knife. The slices are received upon the surface of the 45 slice receiver E . The gauge plate is set at any desired position by the movement of the lever H . The effect of the rotation of this lever about the axis is to impart longitudinal movement to the rod H^8 . This rod, however, is tied to the general gauge plate assembly which includes the member G and the member G^8 which is bolted to it. 50 The member G^8 , by its bosses G^9 , G^{10} , is slidably mounted upon the pins G^{12} , G^{14} which project forwardly from the frame. The slice receiver E , which may be removable, serves to cover and 55 protect the actuating mechanism, including the lever H . The overhang of the gauge plate and flange G^3 prevents any material from getting over the top of the flange E^1 . The bearing sleeves G^9 , G^{10} are forwardly under the carriage D and can 60 readily be reached for adjustment or lubrication. It will be noted that the pins G^{12} , G^{14} extend from the front of the base and are positioned entirely forwardly of the cutting plane. This is advantageous in that they are easily reached, no part 65 of them being housed or concealed at a point where foreign matter may gather or decay.

I claim:

1. In a slicing machine, a base, a knife mounted on the base and means for actuating it, a slice 70 receiver mounted upon said base, a gauge plate, a carriage and means for guiding the carriage across the face of the gauge plate and past the cutting edge of the knife, a forward flange for said slice receiver lying adjacent the cutting 75 plane, and a plurality of guides fixed in relation

to and extending forwardly from the base and supporting means for the gauge plate, lying forwardly of the slice receiver flange and slidably in relation to said guides, and actuating means for the gauge plate positioned on the side of the cutting plane opposite to the guides, said guides being cylindrical in form, the supporting means being provided with apertures through which said cylindrical guides may penetrate, there being a relatively tight fit between one of said guides 10 and one of said apertures and a relatively loose fit between the other of said guides and the other of said apertures.

2. In a slicing machine, a base, a knife mounted on the base and means for actuating it, a slice 15 receiver mounted upon said base, a gauge plate, a carriage and means for guiding the carriage across the face of the gauge plate and past the cutting edge of the knife, a forward flange for said slice receiver lying adjacent the cutting 20 plane, and a plurality of guides fixed in relation to and extending forwardly from the base and supporting means for the gauge plate, lying forwardly of the slice receiver flange and slidably in relation to said guides, and actuating means for the gauge plate positioned on the side of the cutting plane opposite to the guides, said guides being cylindrical in form, the supporting means being provided with apertures through which said cylindrical guides may penetrate, there being a 25 relatively tight fit between one of said guides and one of said apertures and a relatively loose fit between the other of said guides and the other of said apertures, and take-up means associated with the loosely fitting guide and aperture. 30

3. In a slicing machine, a base, a knife mounted on the base and means for actuating it, a slice 35 receiver, a gauge plate, a carriage and means for guiding the carriage across the face of the gauge plate and past the cutting edge of the knife, supporting means for the gauge plate lying forwardly of the slice receiver, and cylindrical tracks for said supporting means, forwardly of and exterior to the base and slice receiver, and extending substantially outwardly from the side of the cutting 40 plane opposite the slice receiver, said supporting means being slidably mounted upon said tracks. 45

4. In a slicing machine, a base, a knife mounted on said base and means for actuating it, a slice receiving means associated with said base and located to the rear of the cutting plane of the knife, a gauge plate, a carriage and means for guiding the carriage across the face of the gauge plate and past the cutting edge of the knife, supporting means for the gauge plate located entirely 50 forwardly of the cutting plane of the knife, and guiding means therefor including track members located entirely forwardly of the cutting plane of the knife and extending forwardly from the base, the base including a forward frame member adjacent the cutting plane, adapted completely to separate the inner ends of said tracks from the interior of the base, whereby the entry of particles of foreign material into the interior of the base is prevented, and actuating means for moving said gauge plate support along said tracks, located to the rear of the cutting plane and beneath the slice receiver. 55

5. In a slicing machine, a base, a knife mounted on said base and means for actuating it, a slice 70 receiving means associated with said base and located to the rear of the cutting plane of the knife, a gauge plate, a carriage and means for guiding the carriage across the face of the gauge plate and past the cutting edge of the knife, sup- 75

porting means for the gauge plate located entirely forwardly of the cutting plane of the knife, and guiding means therefor including track members located entirely forwardly of the cutting plane of the knife and extending forwardly from the base, the base including a forward frame member adjacent the cutting plane, adapted completely to separate the inner ends of said tracks from the interior of the base, actuating 5 means for moving said gauge plate support along 10

said tracks, located to the rear of the cutting plane and beneath the slice receiver and an actuating connection between said actuating means and the gauge plate support, the said base frame member being apertured to permit the passage 5 therethrough of said connection, at a point out of line with said tracks, said connection being at all times out of contact with said frame member.

WILLIAM J. CAMPBELL. 10
